(57) **CLAIM**

The ornamental design for a flying toy, as shown and described.

DESCRIPTION

FIG. 1 is a top view of a flying toy with one surface ornamentation scheme.

FIG. 2 is a front and top view of the flying toy seen in FIG. 1. FIG. 3 is a front and top view of the flying toy with a related surface ornamentation scheme; and,

FIG. 4 is a front and top view of the flying toy with another related surface ornamentation scheme.

The drawing is lined for color. The broken line showing of portions of the flying toy is for the purpose of illustrating portions of the flying toy and forms no part of the claimed design.
